UNITED STATES PATENT OFFICE.

AUGUST F. LUZZI, OF HOUSTON, TEXAS.

ATTACHMENT FOR DENTAL INSTRUMENTS.

1,285,273.

Specification of Letters Patent. Patented Nov. 19, 1918.

Application filed February 6, 1918. Serial No. 215,598.

To all whom it may concern:

Be it known that I, AUGUST F. LUZZI, a citizen of the United States, residing at Houston, in the county of Harris and State 5 of Texas, have invented certain new and useful Improvements in Attachments for Dental Instruments, of which the following is a specification.

This invention relates to new and useful 10 improvements in an attachment for dental instruments.

The object of the invention is to provide an attachment of the character described designed to be secured to the hand piece of 15 the ordinary dental drill for the purpose of protecting the tongue of the patient while the lower teeth are being operated upon, so as to prevent the tongue from being lacerated by the drill or grinding disk.

20 With the above and other objects in view, the invention has particular relation to certain novel features of construction, arrangement of parts and use, an example of which is given in this specification and illustrated 25 in the accompanying drawings wherein:—

The figure shows a perspective view of the device.

Referring now more particularly to the drawing, the numeral 1, designates the hand 30 piece of a dental drill, and the numeral 2, indicates the grinding disk, which operates upon the teeth being treated. This disk is of considerable diameter, and when the lower teeth are being operated upon, it is liable 35 to come in contact with the tongue and lacerate the same. For the purpose of preventing this, I have provided a tongue guard, which is secured to the hand piece by means of a suitable clamp 3, which is formed of 40 flexible material, and clamps around said hand piece. This clamp is formed into an extending arm 4, whose free end carries oppositely disposed, laterally extending wings 5, 5, spaced a sufficient distance from

the disk 2, so as not to contact therewith, 45 and the ends of the wings have a slight outward curve, so as to readily engage under the tongue and hold it spaced from the disk, while the same is in operation.

While the lower teeth on one side of the 50 mouth are being operated upon, one of the wings will perform its required function, and when the lower teeth on the other side of the mouth are being operated upon, the other wing will operate to protect the tongue 55 as described.

The attachment may be readily removed from the hand piece when its use is not required, and may also be readily attached when it is desired to use the same. To facilitate the removal and attachment of the device, the clamp 3 has been provided with a thumb piece 6. When it is desired to remove the attachment, the disk 2 is first removed in the usual way, and then by pressure exerted against said thumb piece, the clamp is gradually forced off of the hand piece; and said thumb piece forms a convenient grip when it is desired to force the clamp back on to the hand piece to bring 70 the attachment into position for use.

What I claim is:—

An attachment for dental grinding instruments including a member adapted to be detachably secured to the hand piece of said 75 instrument, an arm extending from said member and oppositely disposed wings extending laterally from the free end of arm, and whose ends are deflected outwardly from the disk of said instrument. 80

In testimony whereof I have signed my name to this specification in the presence of two subscribing witnesses.

AUGUST F. LUZZI.
